DESIGN FOR AN AUTOMOTIVE WIGWAG STOP SIGNAL

William E. Signor, Gettysburg, Pa.

Application August 14, 1935, Serial No. 58,118

Term of patent 3½ years

To all whom it may concern:

Be it known that I, William E. Signor, a citizen of the United States, residing at Gettysburg, in the county of Adams and State of Pennsylvania, have invented a new, original, and ornamental Design for an Automotive Wigwag Stop Signal, of which the following is a specification, reference being had to the accompanying drawing, forming part thereof, in which the figure is a perspective

view of said automotive wigwag stop signal showing my new design. The appearance of the opposite side face of the figure disclosed is kept substantially plain.

I claim:

The ornamental design for an automotive wigwag stop signal, as shown and described.

WILLIAM E. SIGNOR.
